To all whom it may concern:

Be it known that I, Peter Eduard Geldhof, a citizen of the United States and a resident of the city of Benton Harbor, in the county of Berrien and State of Michigan, have invented a new, original, and ornamental Design for a Combination Washing and Drying Machine or Similar Article, of which the following is a specification, reference being had to the accompanying drawing, forming a part thereof.

On the drawing:

Figure 1 is a frontal perspective view of the combination washing and drying machine or similar article showing my new design;

Figure 2 is a rear view thereof.

The other side of the machine from that shown in Figure 1 is like the side shown in this figure.

I claim:

The ornamental design for a combination washing and drying machine or similar article, as shown and described.
